UNITED STATES PATENT OFFICE.

MOSES M. FIELDS, OF PALESTINE, TEXAS.

HAY-PRESS.

1,190,393.

Specification of Letters Patent. Patented July 11, 1916.

Application filed October 8, 1915. Serial No. 54,780.

To all whom it may concern:

Be it known that I, MOSES M. FIELDS, a citizen of the United States of America, and resident of Palestine, in the county of Anderson and State of Texas, have invented 5 certain new and useful Improvements in Hay-Presses, of which the following is a specification.

This invention relates to presses and particularly to a press designed for use in baling, the primary object of the said invention being to produce a press capable of simultaneously compressing material to form two bales within a single hopper or casing, said 15 hopper or casing being suitably divided.

A still further object of this invention is to provide a casing having means for securing one side in place so that it may be readily removed for the purpose of taking out 20 the bales which are compressed in said casing and the invention furthermore resides in novel means for operating the followers or compression heads, whereby the bales are formed.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, and in 35 which—

Figure 1 illustrates a view in elevation of a press embodying the invention; Fig. 2 illustrates a vertical sectional view thereof; Fig. 3 illustrates a transverse sectional view; 40 Fig. 4 illustrates a top plan view; Fig. 5 illustrates an end view; and Fig. 6 illustrates a view in perspective of a portion of one of the partitions.

In these drawings 7 denotes a base on 45 which the casing is built, one side and the ends thereof being of a rigid structure and the other side being formed by the doors 8 and 9, the said door 8 being movably mounted in the casing by the hinges 11 and the door 9 being movably mounted on the casing by the hinges 12. Each door comprises 50 the strips 13 and 14, which carry the panels 15 and 16, the said panels being separated intermediate the length of the strips 13 and 55 14 to form the space 17. As the doors are practically duplicated, description of one

will suffice as a description of the other and it is noted that the purpose of the space 17 is to form a clearance for the reception of a tongue 18 which projects from one edge of the transversely disposed partition of which the element 19 is a part, the said partition being constructed to two transversely extending plates 20 and 21 between which the element 19 is secured, so that the tongue 18 60 thereof projects beyond the edges of the plates 20 and 21. Plates 20 and 21 are furthermore provided with vertically disposed slots 22 and 23 respectively extending a portion of their height and these slots 70 constitute clearances or ways in which the press beam 24 is movable, the said press beam being provided with followers or heads 25 adapted to engage the contents of the casing for pressing the same.

The upper door is held closed by latches 26, whereas the lower door, which sustains the pressure due to the action of the beam and heads, is held in closed position by rods 27 and 28 having angularly extending ends 80 29 and 30 respectively, which angular ends overlie the sides of the door strips and prevent movement of the said door with relation to the casing. When said door is to be opened, however, the rods may be rotated to 85 cause a disengagement of the angular ends thereof from the door strips and the said door may then be swung on its hinges.

By reason of the presence of the tongue 18 which enters the space 15 between the door 90 panels, a joint is produced between the partition and the door which will prevent the escape of the contents of the casing while said contents is being pressed and the door may be removed from the partition and the 95 tongue thereof, as it swings on its hinges. As shown in Fig. 2, the partition has an aperture 31 in which the rod 27 is seated and rotates.

As a means for operating the presser 100 beam, racks 32 and 33 are provided, one at each end of the casing and these racks have a double set of teeth for a purpose to be presently explained. The beam 24 consists of two side plates 34 and 35 between which 105 the racks are placed and the said beam has a link 36 pivoted near each end, the said link at each end being adapted to engage the outer series of teeth of the ratchet. Near each end of the beam, there is a hanger 37 110 on which a lever or handle 38 is pivoted and each lever has a link 39 pivoted to it at its

inner end, each of said links being adapted to engage an inner series of teeth of the said rack. From an inspection of Fig. 1 of the drawing it is evident that the oscillation of 5 the handle or lever 38 will result in operating the presser beam and that it will be pulled downward upon downward pressure of the outer end of the lever and that upon upward movement of the outer end of the 10 lever, the link 39 may be caused to move into engagement with the next succeeding tooth of the rack so that by again moving the outer end of the said lever downward, further pull on the presser beam will be effected for the purpose of compressing the 15 contents of the casing.

I claim—

In a press, a casing including hinged

doors, said doors having panels spaced apart, a partition extending transversely of 20 the said casing, said partition having a member projecting into the space between the panels of the doors, means for holding the doors closed, means for compressing material in the casing, said partition having an 25 opening therein, a rod rotatable in said opening, said rod having an angularly disposed end for engaging the door for holding it in closed position, and means for compressing material in the casing.

In testimony whereof, I affix my signature in the presence of two witnesses.

MOSES M. FIELDS.
